(57) **CLAIM**

I claim the ornamental design for a lighting device, as shown and described.

DESCRIPTION

FIG. 1 is a top right front perspective view of the design in a retracted configuration;

FIG. 2 is a bottom rear perspective view of the design in the retracted configuration;

FIG. 3 is a front view of the design;

FIG. 4 is a rear view of the design;

FIG. 5 is a left side view of the design in the retracted configuration;

FIG. 6 is a right side view of the design in the retracted configuration;

FIG. 7 is a top view of the design in the retracted configuration;

FIG. 8 is a bottom view of the design in the retracted configuration; and,

FIG. 9 is a top right front perspective view of the design in an extended configuration.

The broken line showing represents unclaimed portions of the article and forms no part of the claimed design.

1 Claim, 5 Drawing Sheets
